**FLOW CONTROL MECHANISM FOR COUNTING-
PACKAGING APPARATUS AND ELECTRIC CIR-
CUITRY THEREFOR**

James W. Batchelder, Ascutney, Vt.

Application June 25, 1957, Serial No. 667,797

18 Claims. (Cl. 53—59)

The present invention is concerned with a mechanism for controlling at desired times the rate of flow of a series of objects moving in soldiered array along a definite path and with electric circuitry therefor. More specifically the present invention is concerned with an improvement on the type of control mechanism of the character disclosed in my co-pending application Serial No. 369,161, filed July 20, 1953, and also with improvements on the control circuitry therefor.

In my co-pending application above identified, a mechanism, in broad sense similar to the present invention, is disclosed in the environment of a machine for packaging articles such as screws, bolts, rivets or the like in exactly counted lots. The packaging machine includes a bulk loaded hopper feeder machine discharging the objects to be packaged in soldiered or serial array along a feeder discharge track whence they drop to a filling station occupied by a box to be filled in exactly counted lot, a succession of boxes being presented at the filling station automatically by a conveyor and box escapement mechanism. In the aforementioned application, and also this application, there is disclosed a so-called track wheel assembly as a mechanism controlling the discharge of objects to the filling station.

In the former application this assembly comprises a pivotally mounted base tiltable toward and away from the discharge track about an axis perpendicular to the track plane, and carrying a rubber tired motor driven wheel mounted for rotation in the plane of the track to engage objects thereon. Also mounted on the base as part of the assembly is an electric motor unit including an electromagnetic brake and a speed reduction gearing unit for driving the wheel at low rotational speeds. The motor and brake are so wired as a unit that upon supply of power to the motor unit, the brake is simultaneously electromagnetically released against a brake engaging bias spring, and upon cut-off of motor power the brake is engaged to stop wheel rotation. The entire assembly is biased either by gravity or by a spring normally to tip the assembly to bring the wheel into engagement with objects flowing in the track; and solenoidally withdrawn against the bias to withdraw the wheel from the track. Thus with the wheel stationary and engaging an object or objects on the discharge track, discharge to the filling station is stopped; with the wheel drawn away from the track, maximum unimpeded flow is permitted; and with the wheel slowly rotating and shifted back to the track, discharge is impeded and limited to a rate determined by the peripheral wheel speed drawing objects thereunder allowing a terminal control operation to be quite exactly timed with respect to the discharge of a particular object. The terminal control operation in the described environment is the stopping of the motor, hence discharge, immediately after the last object of a desired lot count is discharged from the track.

Accordingly with circuitry such as that disclosed in said application or for a modified box escapement clutch in the now Patent 2,792,031, a track wheel assembly of the general character here discussed is adaptable to incorporation in an exact photoelectrically counted pack-

2

aging machine, including box conveying and escapement means presenting boxes individually to a filling station; the track wheel assembly functions above outlined serving to release objects for counted free flow, then to reduce flow for exact final counting, and to stop flow when exact count is reached.

Hence in those disclosures the counter and track wheel assembly cooperating therewith for exact count are integrated for cyclic control and operation with an escapement mechanism of the box conveying and positioning apparatus, so that the filling and counting apparatus function and box replacement or escapement function alternate with each other as long as boxes are available in the conveyor and the hopper feeding mechanism is discharging work pieces.

Although in consequence of the track wheel assembly and associated circuitry, the previously disclosed apparatus is a great improvement both structurally and in quality of function over analogous apparatus which had been proposed by the prior art, all advantages of the broader inventive concept are not realized in the particular structure and circuitry disclosed. Under certain circumstances of quite infrequent occurrence, but nonetheless undesirable, objects might be permitted to discharge from the track at improper times. Also in the track wheel and motor assembly a gyroscopic effect involved in tilting the entire assembly has been found undesirable as overloading the motor bearings; and further the repeated starting and stopping of a relatively high speed electrically braked motor is preferably to be avoided.

One object of the present invention is the provision of a drive system for the track wheel such that no appreciable rotating masses are subjected to an angular change in the direction of axes of rotation when the wheel is shifted relative to the track, and in which further the parts shifted in control operation are of relative small mass. A further object is the provision of a drive system wherein the motor and reduction gearing is continually driven, so that there is no necessity for starting and stopping comparatively large rotating masses during each cycle of control operations. A further object is the provision of a wider range of adjustment of the wheel relative to the track achieved in a more convenient and precise manner than with previous analogous mechanisms.

These several objects are attained by the use of a base, whereon both the drive motor and reduction gearing are secured, which is movable with respect to the track only for adjustment purposes; and further by the use of a solenoidally operated axially shiftable cone clutch and brake mechanism coaxial with the track wheel shaft, the driving clutch member of which carries a gear in constant mesh with the output gear of the reduction unit; and further by pivotally mounting the entire sub-assembly of wheel, clutch and brake unit and solenoid to swing about an axis aligned with the reduction gearing output shaft for moving the wheel to and fro relative to the track by solenoidal means adjustably secured to the base. The structure as subsequently disclosed provides for a very fast action in the transition from braked wheel to clutched wheel condition both by reason of the disclosed clutch and brake mechanism and also by reason of the relatively small masses involved.

With respect to circuitry it is a further object to provide, control means adapted to this improved form of track wheel assembly; and also to avoid the above mentioned and certain other difficulties sometimes arising by carelessness of operation or maintenance. These objects are here attained by the provision of time delay circuit branches as hereinafter more fully set forth.

Other objects and advantages will appear from the following description and the drawings wherein:

Fig. 1 is a side elevational view of the track wheel assembly of this invention, showing its disposition relative to a discharge track and track wheel assembly supporting frame;

Fig. 2 is an irregular axial sectional view, taken as indicated by the line 2—2 in Fig. 1, through the sub-assembly comprising a solenoidally operated brake and clutch unit, and the track wheel operated thereby;

Fig. 3 is a fragmentary sectional view taken at 3—3 in Fig. 1;

Fig. 4 is a detailed sectional view, taken along the line 4—4 in Fig. 1, to show the adjustable mounting of the wheel withdrawal or track solenoid; and

Fig. 5 is a schematic representation of circuitry involved in this invention.

In Fig. 1 of the drawings there is represented in dashed outline the lower end or discharge portion of a feed track mechanism T down which flow work pieces P in soldiered array for continuous successive discharge from the bottom of the track, the flow however being subject to the control of a track wheel assembly of this invention. As an example of a particular environment of use, the structure T may be comprised of a pair of spaced parallel inclined stationary rail elements as the discharge of a bulk loaded hopper feeder machine, which receives say headed pieces such as rivets or screws, orders the same suspended on the track with heads supported on and shanks between the rails, and discharges the work pieces from the end of the rails downwardly into a container filling station of a packaging machine such as that discussed by the introduction of this specification.

The principal components or structures in the drawings (designated by general reference characters) are a supporting frame F; an adjustable base B, supporting a normally continuously running track wheel driving electric motor M, and a speed reduction gearing unit G driven thereby; a track wheel W disposed generally coplanar with the vertical plane of the discharge track T; a clutch and brake unit C rotatably mounting wheel W in the plane of the tracks, and pivotally supported on base B to swing the wheel toward and away from the tracks; a clutch and brake unit solenoid S (see Fig. 2), carried on the unit C; a track solenoid R mounted on the base as a motor means for pivoting the wheel toward and away from track T; and an adjustable parallelogram type linkage L whereby the base B and therefore the entire assembly may be located at selected adjusted position relative to track T.

The base B, a generally flat plate, has a pair of spaced parallel dependent flanges between which the upper ends of a pair of similar link plates 11, 12 are pivotally secured respectively on fixed transverse parallel rods 13, 14. The lower ends of the links are pivotally mounted on a second pair of horizontal rods 15, 16 parallel to and having the same spacing as rods 13, 14, and having ends secured to the frame F. In Fig. 1, the horizontal bar 18 and the vertical bar 19 supporting the right end of 18, represent in fragmentary fashion a rigid frame including a second set of horizontal and vertical bars spaced behind 18 and 19 in parallel fashion to provide clearance with respect to the linkage L and the other elements of the assembly as may be required. The lower pivot rods 15, 16 are bolted at respective opposite ends to the horizontal frame bars 18 and transversely thereto.

The forward link plate 12, hence the base plate, is maintained in selected position between a pair of collars 21, 22 secured on rod 16 by set screws, as seen in detail Fig. 3. A lever 23, interposed on rod 16 between collar 22 and link plate 12 is constrained to pivot with the latter on rod 16 by a pin 24 projecting from plate 12 into a slot 25 milled into the adjacent face of an integrally formed lever lug 23a. The lower end of lever 23 is bifurcated to accommodate the inner end of an elongated knurled head adjusting screw 26 threaded into a pin 27

pivoting in the lever 23 with axis parallel to rod 16. The outer headed end of screw 26 has a swivel seat in and reacts against an eye-bolt-like element 28 mounted on a horizontal bracket bar 29 extending across the vertical frame elements 19. Thus by rotation of the screw 26 to displace pin 27 the lever 23 is swung to move the base B and hence the wheel W for adjustment of the location of the arc of wheel swing relative to the track. Suitable stop nuts and lock nuts may be provided on screw 26.

In the clutch and brake unit C, hereinafter described in greater detail, the housing comprises (see Fig. 2) a hollow member 31, in a tubular extension 31a of which is journaled a shaft 32 carrying wheel W with a broad flat rubber tire; a cover plate 33 journailling a hollow tubular shaft portion 34a of a driving clutch member 34 having sleeve bearings for journailling the inner end of shaft 32 therethrough; and a gear shield 35 mounted on cover plate 33. At the extension 31b of member 31, the unit C is pivotally supported by a fixed pivot shaft 38 between upright ears of a bracket 37 bolted on the forward end of base B, to swing about an axis parallel to shaft 32 and the axes of the parallelogram base mounting linkage L. The output shaft 41 of gearing unit G is aligned with the clutch unit pivot shaft 38, so that the clutch input gear 42, keyed to the tubular shaft 34a of the driving clutch element outboard of cover plate 33, is in constant mesh with gear 43 on shaft 41, irrespective of the pivotal position of the clutch unit C with wheel W.

The solenoid R (Fig. 1) serves when energized to swing the wheel W up away from track T through a link 45 with opposite ends pivotally pinned respectively in aligned vertical slot formations at 46 in the solenoid armature 48 and at 31c in the clutch housing member 31. The solenoid coil 49 is mounted on a rearward plate 50, and the link 45 extends through the opening in a forward plate 51, bolted onto opposite end faces of a slide block 52. The block 52 (see also Fig. 4), held in a slideway formed between parallel guides 54 and respective top plates 55 bolted to base B to overlap parallel longitudinal block shoulders 52a, is movable lengthwise of the base by a solenoid adjusting screw 57 threaded into the rear end of the slide block and having at the knurled headed end thereof a part journaled but axially restrained in an anchor block 58. The forward plate 51 serves as a stop for the armature 48 limiting its forward travel out of solenoid coil 49, when the clutch unit C and wheel W drop toward the track by gravity upon solenoid deenergization. Thus the armature is kept within the influence of the coil flux to insure pick up of the wheel-clutch unit assembly irrespective of wheel position adjustment. Also since the armature stop plate limits the drop of the wheel toward the track, the wheel need not ride the track at any time while in downward position for trickle or reduced flow rate, and pieces on the track are drawn under the wheel without hesitation.

With the structure thus far described it can be seen that a position adjustment of the swingable wheel-clutch unit sub-assembly relative to the track may be made by screw 26 to shift the wheel up or down the track. This adjustment is utilized primarily to set the wheel position as required by the head height and shank length of pieces to be handled, so that the piece is just released as it interrupts a light beam (in the region 101a of Fig. 1) of a photoelectric counting system later described; for greater head heights and shank lengths, the wheel being set the farther up the track; while the closest approach of the wheel to the track is set by moving the solenoid mounting through screw 57.

Considering now in greater detail (see Fig. 2) the clutch and brake unit C, it is first noted that the aforementioned driving clutch member 34 within the housing provided by members 31, 33 has a radial shoulder against which abuts a hardened spacer sleeve 34b journaled in a bearing insert in cover 33; and that the gear 42 is held in axial position against sleeve 34b by a retaining nut 61.

threaded onto the outboard end of tubular shaft portion 34a and there locked by a key washer 62. Thus the input cone clutch member 34 is also secured in axial position by the cover member 33 sandwiched between the opposed radial faces of the member 34 and gear 42.

The rubber tired track wheel W is rotationally engaged with or keyed to shaft 32, but permitted relative axial shift thereon with a minimum of rotational backlash, through a pin 64 tightly fitted in and projecting radially out of the shaft through an axial end slot 65 in the wheel hub into engagement with a pin 66 well spaced radially from shaft 32, the end of pin 64 having a close sliding clearance for motion axially of 66. Thrust bearing washers 67, 68 are located respectively between the hub of wheel W and the end of clutch casing extension 31a, and the outboard end of the hub of wheel W and a preloaded clutch bias compression spring 69. The force of spring 69, reacting through the hub of wheel W upon the clutch housing, is applied through a snap ring 70 engaged in a groove in shaft 32, to bias the shaft outwardly (to the left in Fig. 2) for a brake action to be explained.

For the specific clutch and brake devices 71, 81 within the unit C, the member 34 and the opposed inner end wall of casing member 31 are similarly recessed and in the recesses provided with like internal conform friction surfaces 72, 82, coaxial with shaft 32, each tapering inwardly of the corresponding recess. A collar 80, pinned to the shaft 32, serves as an anchor for a pair of opposed like axially shiftable male cone clutch elements 73, 83 bolted thereto for rotational and axial movement with shaft 32. The outer circumferences of the elements 73, 83 are formed with male coniform surfaces again coaxial with shaft 32 tapering in the same direction as the female cone surfaces to terminate at radial circumferential retaining flanges or shoulders for the helical spring elements 74, 84 actually serving to effect the functional engagement between the cone elements of each device.

The spring elements 74, 84 are helical extension springs each with its ends hooked together, so that the springs are under circumferential tension about the corresponding male cone surfaces. The female cone surfaces are preferably provided by Micarta inserts 75, 85 which have a high coefficient of friction, cemented into corresponding recesses of the housing and of the driving clutch member 34. The inserts are here shown as having a tapered external form, but may be rather exteriorly cylindrical and press fitted into corresponding bores. Moreover it has been found that instead of working against an internal taper of the inserts, each spring effectively engages frictionally with a slightly rounded corner of an insert shoulder or step.

With the described clutch and brake structures, when shaft 32 is shifted to the right of Fig. 2 upon energization of solenoid S as a motor means therefor, through a connection later described the cone clutch 71 engages to couple the continuously rotating driving clutch member 34 to shaft 32 by the wedging action of male cone member 73 carrying the spring 74 into engagement with the narrowing diameter of female cone surface 72, the brake 81 being thereby released. Upon deenergization of solenoid S, the bias spring 69 shifts shaft 32 back to the left to "normal" position, the tension in spring 74 causing the same to snap out of frictional engagement with surface 72 for instant clutch release. At the same time the shift of the shaft, hence of male member 83, carries spring 84 into engagement with the stationary or fixed friction braking surface 82 on the housing to effect instantaneous braking of the shaft 32 and wheel W. The use of a friction member which can roll upon itself in relatively frictionless manner, such as the helical springs 74, 84, permits the use of relatively low taper angles on the conical members and attainment of a relatively high mechanical advantage in the cone-coil contacts without danger of sticking; a point of great advantage in this clutch-brake structure.

The internal action of the brake and clutch elements

upon engagement and release is identical. In all instances the rolling engagement of the spring elements 74, 84 ensures instant release in the axial direction. The axial spacing of the female friction surfaces can be readily varied by shims 90 between the rabbeted edge of casing cover 33 and the mating part of casing member 31 to which the cover is bolted. Likewise the axial spacing of the male cone elements may be varied by shims between the collar 80 and one of the male cone elements as at 91. Both of these adjustments, in varying the axial shift required in the shaft 32 between brake and drive positions, vary the space of, or time of transit through, neutral position, which can be made quite small for rapid action of the unit.

15 The solenoid unit S is supported with its armature plunger 93 in alignment with shaft 32 by the solenoid housing tubular extension 94 inserted in a corresponding bore of a clamping structure 35a of the gear shield member 35. The solenoid coil 95 in unit S serves when energized to draw the shaft 32 to the right against bias of spring 69 for clutch engagement, through a coupling comprising a ball bearing unit 96 with inner race held on the reduced end of shaft 32 by a snap ring, and a coupling sleeve 97 receiving, and by internal snap rings holding, in opposite ends the ball bearing outer race and the solenoid plunger enlargement which are axially spaced by a sleeve 98.

It may be here noted that a work piece directing discharge shield 99 may be adjustably positioned in the region below the wheel W as a laterally projecting element carried on the lower end of an arm 99a in the form of a plate pivotally mounted and held by a snap ring on a shoulder of extension 31a, the arm being split and provided with a clamping screw to secure it in selected position.

30 The track wheel motor assembly thus far described, with the plane of rotation of the wheel disposed in the plane of the track T, may be adjusted as previously indicated to bring the wheel at downmost position, that is with track solenoid R deenergized, to such position that the wheel perimeter is close to touching the top of the track at its bottom-most region, so that with the wheel W rotating slowly the workpieces P will be discharged under the wheel at a slot rate and with the wheel stopped the discharge of work pieces will be stopped; while with the wheel drawn back by energization of solenoid R, the work pieces can flow at maximum rate.

To carry out the presentation of this invention in relation to a particular environment of use, the electrical diagram of Fig. 5 shows in schematic form suitable control elements for the track wheel assembly, as used for photoelectric counting of work pieces in a box conveying and filling apparatus of the character discussed in the introduction of this specification. In such apparatus a continuously driven conveying means carries boxes to an escapement mechanism adapted to present successively individual containers to and retain them in a filling station beneath the discharge point of the track F. The escapement mechanism in a single escapement cycle impels a container into the filling station, simultaneously expelling a previously filled container, and upon termination of the cycle accepts another empty container for presentation in the following escapement cycle. The escapement drive includes a continuously rotating driving shaft from which escapement motion is derived by an electromagnetically or solenoidally actuated single cycle clutch with a microswitch under the influence of an element on the driven side of the clutch serving to terminate the driving relation at the end of a cycle of escapement operation. At the filling station another switch is located to be actuated by a container as it reaches proper position therein, for triggering a work piece counting and release mechanism.

In the diagram, a main switch 110 is provided for connecting of the separately fused main lines 111, 112 to the power source; and drive motor 113, 114, respectively for a hopper feeder supplying track F and for container

conveying and positioning escapement mechanisms, are individually connected across line 112 and a branch 111a taken off 111 before the fuse therein, which then serves to fuse only certain important control circuit branches. Other conventionally used and located fuses and overload protective devices are omitted for clarity. However to assure that, in putting the controlled apparatus into operation, the several control circuits—particularly the electronic counter later described—are in readiness, before the clutch escapement is initially actuated, a time delay relay coil R7 in series with its normally open self-holding contacts R7b across lines 111, 112, is subject to control of the normally open time delay contacts TDC in parallel with the contacts R7b. The time delay heater TDH in series with normally closed contacts R7a across lines 111, 112, requires a certain delay period to heat up and close the thermally responsive contacts TDC, thereupon energizing relay coil R7 to close its normally open contacts R7b, R7d and open the normally closed contacts R7a to cut off the heater.

A relay coil R3, its normally open self-holding contacts R3a, and the normally open microswitch MS₁ serving as the aforementioned switch associated with the single cycle clutch, are connected in series across lines 111a, 112; and the manual push-button starting switch 116 and in series therewith normally open relay contacts R7d, are a control branch (for relay R3) in parallel with the branch R3a and MS₁. The normally open relay contacts R11a and R1a are in series between relay coil R3 and line 111, and therefore also effectively are a branch in parallel with the branch of R3a and MS₁, though separately fused. The escapement clutch solenoid 118 and the normally open contacts R3b of relay R3, connected across 111, 112, complete the primary control circuitry of the escapement clutch.

From the above it may be seen that the starting push button 116 is inoperative until the time delay heater has served its function in delaying closing of R7d. Thereafter momentary closure of 116 will energize R3, simultaneously closing its self-holding contacts R3a and also contacts R3b to energize the clutch solenoid 118, so that the escapement clutch gets under way closing normally open clutch microswitch MS₁ to permit the self-holding contacts R3a to be effective. The escapement clutch mechanism is thus maintained engaged upon release of the push button until MS₁ is permitted to open near the very end of the escapement cycle (which may be completed by inertia), thereby deenergizing R3 and releasing R3a, R3b to deenergize the clutch solenoid. Thereafter in continued automatic operation, with R11a being closed continually, upon each momentary closure of R1a in response to a signal impulse R3 is energized and the cycle is carried out in the same manner as explained for use of 116.

With an electric lamp 101 and a photoelectric cell 102 disposed on opposite sides of and below track F so that each piece P discharging from the track interrupts the light beam focused on the cell, a corresponding impulse or signal is produced by the cell fed to an electric or electronic counting apparatus 120, the power input leads of which are connected across 111, 112. The counter is adapted to be preset to give a final signal output or impulse at a selected final count of pieces discharged from the track, and also to produce a warning impulse or signal at a preselected number before the final count. The counter could be self-clearing, but preferably is reset by closure of a switch means, such as the normally open contacts R6c of relay R6.

Various such counting apparatus are known and commercially available in suitable form, and since the design of the same is not per se a part of this invention it is no further detailed except to note that the aforementioned normally open contacts R1a and the later described normally closed contacts R1b are part of a relay of the

counter energized by the final count impulse to close and open the same respectively; and the later-described normally closed contacts R2a are part of a second relay of the counter energized by the warning impulse to open the same.

The track wheel driving motor M has its leads connected to the variable tap or contact and one end of a variable potential device such as a "Variac" transformer 121 powered from lines 111, 112, and the motor is of such character, such as a series motor, that its speed may be adjusted under operating conditions by setting 121.

The contemplated mode of operation, in the described environment of the present invention by way of example, is that the rubber-tired track wheel W be stationary and 15 in contact with the work pieces on track F during the escapement cycle; and that after a container arrives in the filling station, actuating a suitable device such as the double throw microswitch MS₂ (to be described), the solenoid R be energized to draw the wheel away from 20 the track to allow free counted flow of the pieces, until a warning impulse is generated by the counter. Thereupon, the wheel, already slowly rotating due to preceding maintained energization of solenoid S, is allowed to drop back toward the track in consequence of deenergization of solenoid R, engaging pieces P which then 25 discharge only at the low rate or trickle flow permitted as they pass under the wheel. With slow wheel rotation and with the photocell and lamp close to the end of the track, when the final count impulse is attained, solenoid 30 S is deenergized and the wheel instantly braked before another screw can pass under the wheel.

Relay coil R11 and its self-holding normally open contacts R11b are in series across 111, 112 and the contacts R10a of relay R10 are in parallel with contacts 35 R11b. Track motor relay coil R4, its normally open self-holding contacts R4b, and normally closed contacts R1b of the counter final count relay; and the similarly disposed track solenoid relay coil R5, its normally open contacts R5b, and the normally closed contacts R2a of 40 the counter warning count relay, constitute similar branches across lines 111, 112, which branches are joined at the inner ends of relay coils R4 and R5, by the two sets of series connected contacts R6a and R6b (of relay R6) respectively.

The box tripped double throw microswitch MS₂ (at the box escapement) has one point, with which its arm is normally in contact, connected to the common point of slow release contacts R6a and R6b and its other point connected to one end of the coil in the slow release 45 50 D.C. relay R6. A charging circuit branch comprised of resistor 124, selenium rectifier 125 and capacitor 126 is in series across lines 111 and 112, with a resistor 127 in parallel with capacitor 126. The arm of MS₂ is connected to the line 111 commonly with one side of the 55 capacitor 126; and the other end of slow release relay coil R6 to the opposite side of the capacitor.

Thus with MS₂ in its normal position and R6a and R6b open as shown, capacitor 126 is being charged. Instantaneous contact with the other point (upon transit of 60 a box into the filling position) energizes relay coil R6 by shunting it across capacitor 126 and resistor 127, and putting it in series with rectifier 125 as a D.C. source, closing contacts R6c to reset the counter and also closing R6a, R6b. As R6 is a slow release device, these contacts of R6 remain closed for a time after MS₂ returns to normal position so that relays R4 and R5 are energized, thereby closing respective contacts R4b and R5b for self-holding, since both R1b and R2a are normally 65 closed.

70 As the track solenoid R is in a series branch across 111, 112 comprised of a manual cut-out toggle switch 130, solenoid R, the normally open contacts R5a of relay R5, and normally open relay contacts R8a, were the latter shorted out (and switch 130 of course closed), the

energization of relay R5 in closing contacts R5a would cause an immediate lifting of the track wheel to permit instantaneous work piece flow upon tripping of MS₂ by a box.

In similar manner, since the normally open contacts R4a are in a series branch across 111, 112 comprised of the brake releasing and clutch-engaging solenoid S (of track motor clutch-brake unit C) and normally open contacts R9a of the track timer relay R9, were R9a shorted out, energization of relay R4 in closing contacts R4a would cause immediate brake release and clutch engagement and therefore wheel rotation; which, even if the track wheel were not lifted would cause some pieces to be discharged under the wheel.

Hence to ensure sufficient time for complete resetting and readiness of the counter, not only is the counter reset positively by contacts R6c upon actuation of MS₂, but further a track motor delay timer circuit and a track solenoid delay timer circuit are used involving the aforementioned relay contacts R9a and R8a withholding direct control of the solenoids for a time from R4a and R5a respectively.

These delay timer circuits are essentially identical, each including a full wave selenium rectifier 132 forming across one diagonal a direct series connection with the respective contacts R4a or R5a between lines 111, 112 so that these contacts control directly only the power into the rectifiers. Three successive resistors 133, 134, 135 in series with the relay coil R9 or R8 are connected in series across the other diagonal of the respective rectifiers. A capacitor 138 and normally closed contacts R9b are series connected as a branch parallel to relay coil R9 and resistor 135, with the normally open contacts R9c and resistor 139 as another branch in parallel with capacitor 138. Capacitor 138, normally closed contacts R8b, relay coil R8, resistor 135, normally open relay contacts R8c and resistor 139 are similarly connected in the other delay circuit.

The relay coil R10 for the previously mentioned contacts R10a is likewise connected in series with R4a directly across lines 111, 112 and upon an initial closure of R4a, closes its contacts R10a to energize holding relay coil R11, which in turn closes its contacts R11b (for self-holding thereafter until the power switch 110 is opened) and also to close R11a, permitting control of R3 and escapement initiation to R1a.

By the inclusion of such delay timer circuits with appropriate circuit constants, the charging rate of the capacitors 138 is determinative of the delay time, for the pulsating D.C. derived from a 60 cycle A.C. source is effectively by-passed about the relay coils, for a time until a certain charge and counter-potential is built up on 138; at which instant the current increasing in the relay coils reaches such value as to actuate the same, closing the contacts R9a and R8a to energize S and R to start the track wheel revolving (by clutch engagement) and to lift the wheel, to permit full work piece flow from the tracks.

When the warning count is reached causing relay contacts R2b to open for an instant, R5 is deenergized, opening R5b and R5a, to deenergize R and permit the slowly rotating wheel to drop to the track to initiate trickle flow. At the same time the track solenoid delay circuit is switched off, R8 is deenergized, releasing its contacts to normal position and discharging the capacitor.

In like manner, when the final count signal is reached, opening R1b for an instant, relay R4 is deenergized opening R4a (and also R4b) to deenergize solenoid S releasing the clutch in unit C and causing instant braking of wheel, thereby stopping work piece flow. Opening of R4a in cutting off power to the track wheel delay timer circuit causes a similar restoration of normal contact positions and discharge of the capacitor therein.

Also the final count impulse closes the normally open contacts R1a, and with R11a being maintained now closed, the cycle of the escapement mechanism is again initiated.

5 Since the reset signal or impulse is derived from operation of the microswitch MS₂ rather than from the final count signal, any excess pieces fed to one box will not be recorded or held in a total carried over to a succeeding box. A succeeding box is under the track discharge point at the time the reset is made. Therefore all screws appearing in any count must necessarily go into the corresponding box.

By the use of the time delay heater unit the push-button 116 is ineffective to displace a box past MS-2 and thereby initiate flow, until the counter and control units are warmed up and operative. Further the inclusion of relays R10, and R11 ultimately controlling contacts R11a in series with R1a ensure that contacts R1a will not be operative, until R11a is closed in consequence of energization of R10 in the first complete operational cycle after starting the apparatus, the first cycle being initiated by pressing start switch 116 as previously described.

The switch 130, normally closed for counting operations involving a considerable number of pieces per lot, 15 may be opened when smaller lots are to be counted, even for counts as low as one piece per lot or box. With toggle switch 130 open, the track solenoid R is rendered inoperative, so that when microswitch MS₂ is triggered by a box a trickle flow immediately ensues 20 which is affected and terminated only by the final count impulse as above described.

I claim:

1. A device for controlling the movement of objects past a control point including a wheel adapted to be 35 held stationary while in a first position in contact with an object at the control point, to be withdrawn from the control point to a second position to permit movement of the object independently of the wheel, to be returned to said first position and rotated at a selected rate to contact with an object passed thereunder at a rate determined by said selected rate, and again held stationary while in said first position, comprising: a supporting base, a drive shaft rotatably mounted on the base, a track wheel, a wheel shaft supporting said wheel, 45 means journaling said wheel shaft and pivotally mounted to said base with the pivot axis parallel to the wheel shaft and aligned with the drive shaft whereby said wheel may be shifted from one to the other of said positions, means for drivingly connecting said drive shaft with said wheel shaft, and means mounted on the base and connected with the first said means for shifting the wheel.

2. A device for controlling the flow of objects serially ordered on a track, including a wheel adapted to be 55 held stationary while in a first position in contact with an object on the track to prevent flow, to be withdrawn from the track to a second position to permit free flow of the objects independently of the wheel, to be returned to said first position and rotated at a selected rate to

60 contact objects passed thereunder at a flow rate determined by the rotation rate, and again held stationary while in said first position to stop the flow, comprising: a supporting base, a drive shaft rotatably secured on the base, a wheel shaft supporting said wheel, means journaling said wheel shaft and pivotally mounted to said base with the pivot axis parallel to both said shafts whereby said wheel may be shifted from one to the other of said positions relative to said track, means for drivingly connecting said drive shaft with said wheel shaft, 65 solenoid means mounted on the base for adjustment toward and away from said pivot axis and having an armature connected with the wheel journaling means for shifting the wheel and stop means for said armature movable with the solenoid means upon adjustment of the solenoid means.

3. A device as described in claim 2 wherein the means for drivingly connecting the drive and wheel shafts includes a pinion on the drive shaft and a gear meshed therewith coaxially carried on the wheel shaft; and said pivot axis is aligned with the drive shaft axis.

4. A device for controlling the flow of objects serially ordered on a track, including a wheel adapted to be held stationary while in a first position in contact with an object on the track to prevent flow, to be withdrawn from the track to a second position to permit free flow of the objects independently of the wheel, to be returned to said first position and rotated at a selected rate to contact objects passed thereunder at a flow rate determined by the rotation rate, and again held stationary while in said first position to stop the flow, comprising: a supporting base, a drive shaft rotatably secured on the base and carrying a drive pinion; a wheel shaft supporting said wheel for rotation therewith; a casing journalling said wheel shaft and pivotally mounted to said base with the pivot axis parallel to both said shafts and aligned with the drive shaft, whereby said wheel may be shifted from one to the other of said positions relative to said track; means for drivingly connecting said drive shaft with said wheel shaft including a driving clutch member journaled in said casing coaxially with said wheel shaft, a gear coaxially secured to said clutch member for rotation therewith and meshing with said pinion, means for shifting said wheel shaft axially relative to said wheel, clutch member, gear and casing, and driven clutch means secured to the wheel shaft for axial shift therewith; and means mounted on the base and connected with the said casing for shifting the wheel.

5. A device as described in claim 4, including wheel brake means including a fixed braking surface on said casing and a brake element supported by said wheel shaft axially shiftably therewith into braking engagement with said surface.

6. A device for controlling the flow of objects serially ordered on a track, including a wheel adapted to be held stationary while in a first position in contact with an object on the track to prevent flow, to be withdrawn from the track to a second position to permit free flow of the objects independently of the wheel, to be returned to said first position and rotated at a selected rate to contact objects passed thereunder at a flow rate determined by the rotation rate, and again held stationary while in said first position to stop the flow, comprising: a supporting base; a continually operating electric motor fixed thereon; a speed reduction unit secured on the base, continually driven by the motor and having an output shaft; a wheel shaft and a rubber-tired wheel keyed thereon for relative axial shift, said wheel shaft being parallel to said output shaft; a casing rotatably axially shiftably supporting said wheel shaft and pivotally mounted to said base with pivot axis aligned with said output shaft whereby said wheel may be shifted from one to the other of said positions relative to said track; a driving clutch member and connected gear rotatably mounted in said casing coaxially on the wheel shaft; a pinion on said output shaft meshed with said gear; a fixed braking member in said casing axially spaced from said clutch member; a driven clutch and brake element secured on said wheel shaft for rotation and axial shift therewith; preloaded compression spring means normally biasing the wheel shaft for wheel braking engagement of said element with said brake member; motor means for shifting said element into driven engagement with said clutch member against the bias of said spring; and motor means mounted on the base having an armature connected with the said casing for shifting the wheel.

7. A device as described in claim 6 wherein said base is supported by a parallelogram linkage on a fixed frame for adjusting movement of the wheel lengthwise of the said track along an inclined discharge end thereof; and

an adjusting screw reacting on said frame is threadably engaged with a part of said linkage.

8. A device as described in claim 6, wherein said casing is comprised of a part mounting said brake member and a second part mounting said clutch member, said parts of the casing being bolted together in axially abutting, relation, with spacing shims therebetween whereby the neutral period between wheel driving and braking may be varied.

10. A device as described in claim 6 wherein said element is comprised of two adjacent members providing axially spaced parts engageable respectively with said clutch and brake members, and spacing shims are interposed between said adjacent members to adjust the neutral period between driving and braking of the wheel.

10. A device for controlling the flow of objects serially ordered on a track, including a wheel adapted to be held stationary while in a first position in contact with an object on the track to prevent flow, to be withdrawn from the track to a second position to permit free flow of the objects independently of the wheel, to be returned to said first position and rotated at a selected rate to contact objects passed thereunder at a flow rate determined by the rotation rate, and again held stationary while in said

25 first position to stop the flow, comprising: a supporting base; a drive shaft rotatably secured on the base; a rubber-tired wheel; a wheel shaft disposed parallel to the drive shaft and axially shiftably supporting the wheel for rotation therewith; a hollow casing journalling said wheel

30 shaft extending therethrough, said casing being pivotally mounted to said base with the pivot axis closely aligned with said drive shaft whereby said wheel may be shifted from one to the other of said positions relative to said track; said wheel being carried on the wheel shaft projecting at one end of the casing; clutch and brake means in

35 said casing including a driving clutch member with a gear secured thereto coaxially journaled on said wheel shaft and in the other end of said casing, axially spaced annular friction elements coaxial to the wheel shaft

40 secured in said one end of the casing and in the face of the driving clutch member as a fixed braking and a clutch surface, means disposed between said annular members fixed on the wheel shaft for rotation and axial shift therewith providing on opposite sides thereof surfaces

45 tapering slightly toward the annular members and terminating in respective end flanges, helical tension springs each with ends joined to form a spring annulus on a respective tapering surface, said springs being under circumferential tension urging the same toward the

50 material having a high coefficient of friction relative to said springs, helical compression spring means operatively disposed between the wheel shaft and wheel to bias the shaft in a direction effecting wheel braking engagement of said braking surface with the adjacent helical

55 spring and release of clutching engagement, means for shifting the wheel shaft against the compression spring means to effect driving clutch surface engagement with the other helical spring; a pinion on said output shaft in constant mesh with said gear; and means mounted on the base and connected with the said casing for shifting the wheel.

60 11. A device as described in claim 10 wherein said means for shifting the wheel shaft includes a solenoid secured on one end of the casing and having therein an axial armature or plunger in axial alignment with said shaft, and means for axially securing the plunger to said wheel shaft but permitting relative rotation therebetween, said means including an anti-friction bearing.

65 12. A device as described in claim 10, wherein said tapering surfaces are provided on separate collar-like elements secured in axial and rotational sense to said wheel shaft, and removable spacing means are provided between said elements for varying the neutral period between braking and clutching engagement.

13. A clutch and brake unit for driving or breaking a shaft comprising: a hollow casing journaling said shaft extending therethrough, clutch and brake means in said casing including a driving clutch member coaxially journalled on said shaft and in one end of said casing, axially spaced annular friction elements coaxial to the wheel shaft secured in the other end of the casing and in the face of the driving clutch member respectively a fixed braking and a clutch surface, means disposed between said annular members fixed on the shaft for rotation and axial shift therewith providing on opposite sides thereof surfaces tapering slightly toward respective annular members and terminating in respective end flanges, helical tension springs each with ends joined to form a spring annulus on a respective tapering surface, said springs being under circumferential tension urging the same toward the respective flanges, said annular members being formed of material having a high coefficient of friction relative to said springs and each presenting on its internal circumference a circumferentially extended surface adapted for cooperation with a respective said tapering surface to effect a wedging engagement of a helical tension spring therebetween, helical compression spring means operatively disposed between the shaft and an axially fixed element to bias the shaft in a direction effecting wheel braking engagement of said braking surface with the adjacent helical spring and release of clutching engagement, and means for shifting the shaft against the compression spring means to effect driving clutch surface engagement with the other helical spring.

14. A device as described in claim 13 wherein said means for shifting the shaft includes a solenoid secured on one end of the casing and having therein an axial armature or plunger in axial alignment with said shaft, and means for axially securing the plunger to said shaft but permitting relative rotation therebetween, said means including an anti-friction bearing.

15. A device as described in claim 13 wherein said flanges are so disposed relative to each other and to said annular members that each tension spring when in non-engaged relation with the corresponding annular member is in non-driving contact therewith.

16. In combination with a device as set forth in claim 11, counting and control circuitry adapting the same for automatic cyclic operation with an apparatus including track means feeding objects to a box filling station, escapement means presenting boxes successively to the station, and electrically energized means for carrying out an escapement cycle, said circuitry including: a photoelectric counting head viewing the discharge region of said track and an electric counter receiving signals from the head and having a final count relay with normally closed and normally open contacts adapted to open and close respectively on reaching a preselected final count, and a warning count relay with normally closed contacts adapted to open when a count of preselected number before final count is reached; a circuit branch including said normally open final count contacts adapted to initiate an escapement cycle; a starting push button in series with normally open relay switch means as a second branch in parallel with the first, to initiate a first escapement cycle, and a time delay circuit closing said switch means a pre-selected time after beginning operations; a single pole double throw switch momentarily actuated to open normally closed contacts therein and close normally open contacts upon being tripped by a box entering said filling station; slow release direct current relay means energized by tripping of the double throw switch to close three sets of normally open contacts, a first set resetting said counter and the other sets initiating operation respectively of a wheel control solenoid, and wheel shift solenoid, through respective self-holding relay circuits maintaining said operation; time delay circuits to delay energization of said solenoids a selected period of time to permit resetting the counter, said normally closed final and warn-

ing count relay contacts being included in said self-holding relay circuits to terminate the respective solenoid energization at warning and final count to shift the wheel to the track and to brake the wheel.

5 17. The combination as set forth in claim 16 wherein said normally open final count contacts are in series with relay switch contacts withholding control therefrom and a circuit energized by initial closure of one of said sets of direct current relay contacts to effect closure of the control withholding contacts, the last said circuit being adapted to keep the control withholding contacts closed after initial energization.

10 18. In combination with a device as set forth in claim 11, counting and control circuitry adapting the same for automatic cyclic operation with an apparatus including track means feeding objects to a box filling station, escapement means presenting boxes successively to the station, and electrically energized means for carrying out an escapement cycle, said circuitry including: a photoelectric counting head viewing the discharge region of said track and an electric counter receiving signals from the head and having a final count relay with normally closed and normally open contacts adapted to open and close respectively on reaching a preselected final count, and a warning count relay with normally closed contacts adapted to open when a count of preselected number before final count is reached; a pair of main lines connecting to an external electrical power source; a normally open microswitch closed by said escapement means on beginning a cycle and opened thereby to terminate the cycle; a first relay with normally open contacts controlling said electrically energized means, said relay having its coil and normally open holding contacts in series with said microswitch across said lines; a starting push button and start time delay controlled contacts connected in series with each other and as a control branch in parallel with said holding contacts and microswitch; said normally open final count contacts being in parallel with said parallel control branch during automatically continued cycling of the apparatus; a track wheel solenoid control relay having a coil and normally open contacts in series with said normally closed final count contacts across said lines; a wheel shift solenoid control relay having a coil and normally open holding contacts and the normally closed warning count contacts in series across said lines; a direct current slow release relay with a paired set of normally open contacts connected in series and across the track wheel and wheel shift control branches at corresponding points between the relay coils and contacts therein, and also having first normally open contacts connected to said counter as a switch to reset the same to zero count; a first time delay circuit controlled by other normally-open contacts of said wheel solenoid control relay and having delay switch means in series with said other contacts and the wheel control solenoid across said lines; a second time delay circuit controlled by other normally open contacts of said wheel shift solenoid control relay having delay switch means in series with said other normally open contacts and the clutch solenoid across said lines; a single pole double throw switch means adapted to be tripped from normally closed setting to close momentarily upon a normally open contact by a box entering said filling station, the normally closed contact of the last said switch means being connected to a common point of the paired contacts of the direct current relay, and the movable contact arm to one of said lines, and the normally open contact to one end of the coil of said direct current relay, the other end of the last said coil being connected to the other said line.
